UNITED STATES PATENT OFFICE.

JOHN ALGERNON LAUNDER, OF NEWCASTLE-UPON-TYNE, ENGLAND.

GARMENT-DISPLAYING DEVICE.

1,410,930.

Specification of Letters Patent. Patented Mar. 28, 1922.

Application filed February 28, 1920. Serial No. 362,144.

To all whom it may concern:

Be it known that I, JOHN ALGERNON LAUNDER, a subject of the King of Great Britain and Ireland, residing at the city and county of Newcastle-upon-Tyne, England, have invented new and useful Improvements in Garment-Displaying Devices, of which the following is a specification.

This invention relates to garment-displaying devices, and has for its object to provide an improved device for displaying a garment carried by a garment-supporting shoulder so that the shoulder and the garment carried thereby can be removed from 15 and replaced upon the displaying device without disturbing the latter.

A garment-displaying device in accordance with this invention comprises a shank which carries a vertical supporting frame 20 provided with a plurality of hooks in front of its upper portion on which loosely rests a garment-supporting shoulder. The shank of the device may fit into a socket in the upper end of an upright stand provided 25 with a base to stand upon the floor, or into a socket carried by a wall-bracket.

The supporting frame may be made of strong metal wire or of wood or other suitable material.

30 I will fully describe my invention with reference to the accompanying drawings wherein—

Figure 1 is a front elevation of a garment-displaying device in accordance with my invention fitted to an upright stand; and

Figure 2 is a side elevation thereof.

Figures 3 and 4 are similar views to Figs. 1 and 2 of the device fitted to a wall-bracket; and

40 Figures 5 and 6 are part similar views to Figs. 1 and 2 of a modified form of the device.

Referring first to Figs. 1 and 2, the garment-displaying device therein illustrated 45 comprises a shank *a* from which diverge two supporting members *b* extending upwardly and each provided with a hook *c* at its upper end. A rear supporting member *d* extends between the hooks *c*. The supporting members *b*, hooks *c* and rear supporting member *d* together constitute a vertical supporting frame and are formed by bending and looping a single piece of strong metal wire. A garment-supporting shoulder *e* rests loosely 55 on the hooks *c* in front of the rear supporting member *d*, but is not in any way secured

thereto. The shank *a* fits into a socket *f* in an upright stand *g* provided with a base *h*. The shank *a* is rotatable in the socket *f* so that the supporting frame and shoulder can 60 be turned about the axis of said shank to any desired position to display the garment. The garment-supporting shoulder *e* may be formed of cardboard, three-ply wood, compressed fibre, aluminium or other suitable 65 material, and is formed with a hook *j* so that, when it is removed from the supporting frame, it can be hung with others on a rail or other like support.

Figs. 3 and 4 show a slightly modified 70 construction of the garment-displaying device of Figs. 1 and 2 wherein the shank *a* is adapted to fit into a socket *k* carried by a wall bracket *m*, the shank *a* being bent as shown for this purpose.

75 In the modified form of garment-displaying device illustrated in Figs. 5 and 6, the supporting frame is made of three-ply wood or similar material, and comprises an upwardly extending portion *n* carried by a shank *p* and formed integral with a shoulder *q* which may, if desired, be used to support a garment. Hooks *r* are attached to the supporting frame and receive the garment-supporting shoulder *e* which rests 85 loosely on said hooks in front of the shoulder *q*. In the construction illustrated, the shank *p* is adapted to fit into the socket *f* of the upright stand *g* of Figs. 1 and 2, but, as will be obvious, the shank *p* may be 90 adapted to fit into the socket *k* of the wall bracket *m* of Figs. 3 and 4.

With garment-displaying devices as herein described the garment to be displayed is placed upon the garment-supporting shoulder *e*, and the shoulder and garment together are placed on the hooks of the display device without it being necessary to handle or crush the garment. A number of the display devices may be disposed, for example, 100 in a shop window, and the garments can be very quickly arranged and displayed thereon, thus saving a great amount of the time hitherto required for dressing shop windows. At the end of the day all the garments on their supporting shoulders can be 105 readily removed from the window and stored away until the next morning when the garments can be quickly replaced in position on the display stands, thus preventing 110 the damage which is usually done to garments by allowing them to remain in the

windows overnight. It has hitherto been practically impossible to strip and re-dress a window full of blouses or like garments every night and morning owing to the time required when existing display devices are used.

What I claim as my invention, and desire to secure by Letters Patent is:—

In a garment-displaying device, means for loosely retaining a garment-supporting shoulder so that it and the garment it supports can be together readily removed in a vertical direction by lifting the shoulder, comprising, in combination, a shank, means

for supporting said shank in an upright position, two supporting members diverging upwardly from said shank, a hook on the inside of the upper end of each supporting member, and a flatly curved rear member extending between and behind said hooks, said supporting members, hooks and rear member together constituting a vertical frame whereon the garment-supporting shoulder loosely rests between said hooks and said rear member.

In testimony whereof I have signed my name to this specification.

JOHN ALGERNON LAUNDER.
